a corporation of Delaware

Filed Dec. 8, 1961, Ser. No. 67,839

Term of patent 14 years

(Cl. D33—11)

FIG. 1 is a perspective view of a convertible chair-desk or the like embodying our new design, the desk tablet being shown in a lowered position;

FIG. 2 is a perspective view thereof with the desk tablet shown in operative position;

FIG. 3 is a side perspective view thereof with the tablet lowered;

FIG. 4 is an opposite side perspective view, with the tablet in operative position;

FIG. 5 is a front perspective view, with the tablet lowered;

FIG. 6 is a front perspective view, with the tablet in operative position; and

FIG. 7 is a rear perspective view, with the tablet in operative position.

The characteristic feature of our design resides in the

combination on the convertible chair-desk disclosed of an arm rest as best shown in FIGS. 1, 3 and 5.

We claim:

The ornamental design for a convertible chair-desk or the like, substantially as shown and described.
